CUSHION SIDE BEARING

Filed April 19, 1926

UNITED STATES PATENT OFFICE

WALTER L. DOWNEY, OF RICHMOND, VIRGINIA

CUSHION SIDE BEARING

Application filed April 19, 1926. Serial No. 103,020.

The object of this invention is to provide cushion side bearings for use on the body and truck bolsters, either or both of them, of railway cars, which bearings not only perform the usual function of side bearings, but in addition take up the strain of oscillation of the car when in use and cushion the blow on the truck bolsters which is transmitted to the bolster springs, thereby saving much expense in repair work and adding to the security as well as the safety of the cars with such bearings.

The invention consists of a box containing a spring or springs yieldingly held therein by a cover movably secured to the box, the spring or springs being secured within the box under compression, and the parts being readily accessible for assembling and repair purposes, as I will proceed now to explain 20 and finally claim.

In the accompanying drawings illustrating the invention, in the several figures of which like parts are similarly designated, Figure 1 is a top plan view. Fig. 2 is a side elevation. Fig. 3 is a vertical longitudinal section.

The box 1 may be of rectangular cross section, having the bottom lugs 2 for securing it to a bolster, as by bolts or rivets, although the box may be cast or forged integral with the bolster, or welded thereon. The end walls of the box, at their tops, are provided with the laterally extended flanges 3 and the cavity in the box is adapted to receive 35 one or more springs 4.

The cover 5 is of greater length than the greatest over-all length of the flanges 3, and the sides of the cover have the depending flanges 6 in the opposite ends of which are 40 the vertically slotted openings 7 which are located in the flanges beyond the end walls of the box. These openings are designed to receive the keys 8 which are passed through the openings 7 beneath the flanges 3 and are secured therein by cotter pins or other fastenings 9, to permit the vertical movement of the cover and keys. The construction and arrangement is such that the cover is movably connected with the box and yieldable under 45 the action of the spring or springs within

the box, whereby a cushioning effect between the pairs of side bearings is secured. The flanges 6 overlap the side walls of the box and prevent sidewise displacement of the cover, and the cooperation of the flanges 3 with the cover and the keys 8 and their fastenings 9 prevents the endwise displacement of the cover when the parts are assembled on the box.

I have shown the bearing as provided with a single pocket, although it may be constructed with any number of pockets; and the springs used therein may be nested as shown in Fig. 3, or otherwise disposed.

The cover is applied to the box and the springs therein under pressure and while the springs are under compression, and then the keys 8 are applied to the cover and box and locked in position, the action of the springs after being released from the aforesaid pressure serving to lift the cover and provide the necessary clearance for the yielding of the cover in use.

For repair or other purposes, the cover may be readily removed by pressing it down on the box and taking out the cotter and keys, without otherwise demounting the structure.

As already stated, the boxes may be made separate and attached to the body or truck bolsters or both of them, or they may be cast or forged integral with the bolsters or either of them.

The box and its cover plate may be cast or forged, and when the box is made separate, it may be bolted, riveted or welded, or otherwise secured to the bolster.

When a car, supplied with these side bearings, is in vertical position, the top and bottom side bearings on the body and truck bolsters, may be merely in contact and without friction or carrying weight, or there may be clearance between the top side bearing and the bottom side bearing. When one side of the truck falls into a low joint in the track, thereby causing the opposite side of the truck to start oscillations of the body with a sharp blow, the cushioning will sustain the heavy blow to the truck, and instead of the side of the truck striking the low joint coming up or rebounding and striking the

body another blow and thereby starting rolling of the car body, the springs on that side will assist in putting the car body in proper position, but the springs in the cushion side bearings will immediately cease functioning 5 when the opposite bearings come into contact, since the springs have only a limited travel. In other words, the springs in the bearings will stop functioning when the car is in up-right position, thereby preventing any kick-back of one spring against the other.

Some of the advantages incident to my invention are as follows:—In use the cushion side bearing will start at zero side bearing 15 clearance, or more, if desired, and immediately when top and bottom bearings come into contact, oscillation is retarded and cushioned, and there is prevented the building up, by the sidewise rolling, of a dangerous roll, such as 20 would tend to cause the car wheels to leave the rails at certain critical speeds, thereby keeping the heavy oscillations down under eight miles an hour. Furthermore, these cushion side bearings overcome practically 25 all tendency of the bolster springs to go solid and breaking or taking a permanent set that is detrimental to them. While the side bearings are designed to permit approximately a quarter-inch travel or clearance before the 30 cover comes solid on the box, it is optional whether this is more or less, and it is governed somewhat by the spacing between the bearings on each side of the car and also by the height of center of gravity of the car and 35 its lading.

It is well known that failures in the bolster springs are the result of the heavy rolling and oscillations of the car body transmitted by the weight of the rocking car through the 40 side bearings and bolsters, and the side bearings of this invention will cushion these blows at the instant they are started. This action results approximately in twenty per cent of the load limit of the bolster springs 45 being absorbed, and, indeed, a very considerable retardation of the oscillations before the bolster springs are called upon to perform the additional work necessitated by the rolling of the car. This retardation in its in- 50 fancy will set up a time element in the oscillations that will approximately decrease the critical speed three times what it is with the constructions commonly used, and consequently the critical speed of heavily loaded 55 cars is put a safe distance below normal operating speeds on railroads. Furthermore, these cushion side bearings will also absorb the sharp blows incident to constructions commonly used, and thereby prevent the 60 breaking of the side bearings; and, moreover, will constantly reduce the effective force of the blows which cause bent and broken bolsters, side frames, arch bars and the like. As already stated, the sharp blows that other- 65 wise would be imposed on the roadbed are ab-

sorbed, and consequently maintenance costs are reduced. Still further, the cushioning side bearings are so designed as not to cause undue friction on track curves.

The maintenance costs of the cushion side 70 bearings would be practically naught, inasmuch as the springs, boxes and covers would last the life of the ordinary car unless given unfair usage.

Variations in the details of construction 75 and arrangement of parts in addition to those mentioned, are permissible within the principle of the invention and the scope of the claims following.

What I claim is:—

1. A cushion side bearing, comprising a box having end and side walls, and laterally extended flanges at the tops of its end walls, a suitable number of springs arranged in said box, a cover of a length greater than the greatest distance between the outer ends of said flanges, said cover having opposite depending flanges overlapping the side walls of the box and provided with vertically slotted openings located therein beyond the end walls of the box and aligned with said box flanges, said cover yieldingly mounted on the springs above the top of the box, and keys arranged transversely of the box in the openings in the cover and beneath the box flanges and outside of the end walls of the box and having vertical movement in said openings, and means to lock the keys in position. 80

2. A cushion side bearing, comprising a box having end and side walls, and laterally 100 extended flanges at the tops of its end walls, a suitable number of springs arranged in said box, a cover of a length greater than the greatest distance between the outer ends of said flanges, said cover having opposite depending flanges overlapping the side walls of the box and provided with vertically slotted openings located therein beyond the end walls of the box and aligned with said box flanges, said cover yieldingly mounted on the 105 springs above the top of the box, and keys arranged transversely of the box in the openings in the cover and beneath the box flanges and outside of the end walls of the box and having vertical movement in said openings, and means to lock the keys in position, the 110 cover being applied to the box while the springs are under compression and when so applied having a clearance which will permit the movements occasioned when the bearing is in service and accessible from the outside for repairs. 115

In testimony whereof I have hereunto set my hand this 17th day of April A. D. 1926.

WALTER L. DOWNEY.
